PROCESS AND APPARATUS FOR WAVING
HUMAN HAIR

William H. Bleuel, Dormont, Pa., and Samuel Steek, Warren, Ohio; said Steek assignor to said Bleuel

Application August 5, 1935, Serial No. 34,788

17 Claims. (Cl. 132—36)

This invention relates generally to improvements in process and apparatus for waving human hair, and more particularly for waving hair by the Croquignole and spiral methods.

This invention may be conveniently applied for waving hair by the method wherein either electricity or steam may be used as the source of heating energy. For convenience in illustrating our invention we have employed the steam method.

The present practice in both methods is to gather the hair in strands and chemically treat the same. A clamp is then applied adjacent the roots of each strand, and the latter is then snugly wound on a mandrel.

In the electric method a felt strip is placed around the hair so as to absorb the vapors or condensate during the heating of the hair and to prevent the same from burning the patient's scalp.

In the steam process the felt is not used as the condensate is collected and drained from the hair as it is formed.

In both methods the wound hair is enclosed in an individual container or box. In the Croquignole method the mandrel is ordinarily held by the clamp but in the spiral method the mandrel is usually held in place by the container.

In both methods precautionary measures must be taken to avoid the burning of the patient's scalp. Pads and protectors of various kinds are generally used in the art for this purpose. However with all these precautions burns frequently result, because of the many opportunities for the escape of condensate or steam from the numerous containers on the patient's head. The average person requires the use of from twenty-four to thirty-six individual curls on the head for a permanent wave. Each curl is enclosed in a box and there are several places through which the condensate may escape if it is improperly installed or if it is old and worn.

Again the quantity of apparatus on a patient's head renders the work difficult owing to congestion or lack of space. In the electric process each box requires two wires to energize the heating coils. In the steam process one or two tubes may be required for each box through which the steam and the condensate are carried. This adds to the congestion and often creates individual pulling strains on some of the hair strands, making it uncomfortable for the patient.

One object of our invention is to provide one, or comparatively a few containers, each of which will hold a plurality of strands of hair while

they are being waved, thus avoiding the weight, congestion and pulling strains.

Another object is to provide a single container capable of carrying a plurality of hair strands, thereby enabling one to more effectively prevent the escape to the patient's head.

Another object is to provide means for cooling the patient's scalp during the process of waving the hair.

Another object is to employ means to quickly cool and carry away any condensate that may possibly leak due to the improper application of the apparatus.

Another object is to provide fluid pressure means for preventing the steam or condensate from escaping to the patient's scalp.

This invention is also advantageous in that individual electric heating elements or a general electric heating element may be used in place of steam. In each case only two wires are needed to carry the current to the patient's head from whence it may branch to the individual curls or the general heating element as the case may be.

In the steam method only one or two tubes are required to carry the steam and the condensate to and from the patient's head, which will be described in detail herein.

Another object is to provide fluid means for sealing the steam and spacing chambers of the hair waving apparatus.

Other objects, advantages and means to effect the same will appear from the following description.

In the accompanying drawings, wherein we have illustrated a practical embodiment of the principles of our invention, Fig. 1 is a sectional view showing the application of our invention to hair waving apparatus using the Croquignole method with steam.

Fig. 2 is a side elevation showing the scalp protector applied to a patient's head.

Fig. 3 is an enlarged vertical section taken through one of the hair strand necks of the scalp protector and spacer.

Fig. 4 is a sectional view taken on the line 4—4 of Fig. 3.

Fig. 5 is a broken perspective view on enlarged scale showing several of the hair strand necks of the scalp protector.

Fig. 6 is a broken perspective showing a strand wound in the Croquignole manner and clamped in place over one of the necks.

Fig. 7 is a view similar to Fig. 1 but illustrating the spiral winding of the hair.

Fig. 8 is a view in horizontal section of the scalp protector shown in Fig. 7.

Fig. 9 is a broken perspective of the scalp protector illustrating the arrangement of the 5 spirally wound strands.

Fig. 10 is a view similar to Fig. 1 but showing a modification.

Fig. 11 is a rear elevation of the structure shown in Fig. 10.

10 Fig. 12 is a perspective view illustrating the channel spacer which the wave chambers show in Fig. 10.

Fig. 13 is a sectional view taken along the line 13—13 in Fig. 12.

15 Fig. 14 is a sectional view showing the spacer cap illustrated in Fig. 10.

Fig. 15 is a sectional view partly broken away and showing the passages also illustrated in Fig. 11.

20 Referring to the drawings and more particularly to Figs. 1 to 8, 10 represents the scalp line of the human head. The hair of the head is divided into strands 11. Each strand is passed through a slot 12 of a spacer or heat insulating pad 13 which 25 is preferably made of absorbent material such as felt. Preferably individual pads are employed for each strand.

14 represents a flexible scalp protector, preferably made of rubber or similar material capable 30 of withstanding a considerable amount of heat without endangering its elastic gripping qualities. This protector comprises a skull cap portion 15 having a scalloped rim 16 which forms an exterior trough 17 where rim joins the skull cap portion.

35 The rim may have any desired shape. However we prefer the scalloped edge and the scallops are provided with snap fasteners 18.

These fasteners are used to hold superimposed 40 apparatus in position. The scallop edge prevents breaking of the turned up rim and facilitates the engagement of the fasteners.

The skull cap portion is provided with a plurality of upwardly extending walls forming necks 19 having throats or passages through the cap. In 45 the Croquignole method the necks are elongated whereas in the spiral method they are ordinarily tubular as in Fig. 7. As shown in Figs. 3 and 4 the throats in the necks 19 are provided with a series of annular ribs 20 which may be oppositely 50 staggered as shown to permit their interengagement when the necks are compressed. Whether employed for the spiral or Croquignole method these ribs assist in gripping the hair as demonstrated in Fig. 4. The kinking of the hair between 55 these ribs prevents it from slipping therethrough when a slight amount of pressure is used to compress the walls of the necks. This feature aids in preventing undesirable strains on the hair strands.

60 The ribs 20 also retard and deflect any seepage of condensate therethrough, thereby preventing scalp burns.

The hair strands 11 are wound on the mandrels 21, which as shown in Figs. 1 and 6 are supported 65 on the clamps 22 whose jaws tightly grasp the lower portion of the necks 19, sealing the hair strands therein.

23 represents a hood or closure member which 70 may be made of rigid material such as aluminum, hard rubber or other suitable material. The hood is made in two sections; a bowl shaped portion 24 and an annular rim portion 25 which spaces the bowl 24 from the scalp protector 14 thus forming the chamber 27.

75 The rim is provided with an inturned lip 26

arranged to fit the groove 17 of the scalp protector 14. The lip has a perimetral contour similar to that of the shape of the human head. However, the wall of the protector 14 is thickened adjacent the groove 17 to compensate for slight uneven 5 contours of the head. This permits the lip 26 of the hood to tightly fit in the groove 17 when the snaps 18 of the scalloped rim are turned up and secured to the buttons 28 on the bowl 24.

The outer perimetral edge of the rim 25 is 10 turned upwardly and arranged to telescope within and snugly fit the bowl. Different sizes of rims may be employed to fit different shapes of heads, yet the perimetral edges of these rims all fit snugly 15 in the bowl 24.

The use of one bowl with several rims permits the operators to prepare several patients for a wave and only one bowl which may be secured to the steaming apparatus is necessary since this bowl merely slides down over the rim and the 20 scalp protector is snapped thereon.

The bowl 24 of Fig. 1 is provided with an annular groove 29 arranged to receive the ring shaped steam header or tubing 30 provided with the ports 31 which direct the steam at all angles within the 25 chamber 27 between the hood 23 and the scalp protector 14. The lower or rearward side of the ring 30 is provided with the outward extending neck 32 for connecting it with a steam, air, or water source designated by the pipes 33, 34 and 35 30 respectively, and which are controlled by the three way valve 36.

The lower or rearward portion of the hood is provided with the neck 37 for connecting the chamber 27 to the waste drain pipe 38. This 35 passageway serves to discharge the chamber 27 of all the condensate, water or other liquids. The top of the bowl 24 is provided with the vents 39 which permit the steam to circulate through the chamber 27 and escape therefrom.

The drain passageway 37 may also be employed 40 both as the steam inlet and condensate exhaust for the chamber 27 as shown in Fig. 7 and in the manner disclosed in our Patent No. 2,009,993 of 45 August 6, 1935.

The apex of the bowl is provided with the opening 40 which may be enclosed with glass to form a window to observe the wound strands after the hood 23 has been positioned in place.

41 represents a direct tube which opens to the 50 inner surface of the scalp protector 23. This tube may be divided by a longitudinal partition into two passages 42 and 43. When the apparatus is in place the patient's scalp may be cooled by air or water by virtue of the tube 41. If air is employed to cool the scalp an edge of the scalp protector opposite the ports in the passageway 41 may be raised from the head to exhaust the air after it has passed over the scalp, or it may be exhausted out of the other passageway in the tube. 60

Referring particularly to Figs. 7, 8 and 9, wherein corresponding parts are designated by the same numerals used to describe similar parts shown in Figs. 1 to 6, the scalp protector of this modification is provided with the tubular necks 19 65 to receive the hair strands 11 for the spiral method of waving hair.

As described above the steam chamber 27 shown in Fig. 7 is supplied with steam through the passageway 37 at the rear of the apparatus. This 70 passageway represents the lowest point in the steam chamber when the apparatus is in place, and the same port is preferably used for continuously discharging the condensate from the chamber during the steaming operation.

The lower portion of the scalp protector 14 is provided with the tubular head band 45 which has passageway 46 for connection to the pipe 47. The front of the tubular band is provided with the holes 48 which permit the passage of fluid from the band to the space between the scalp protector 14 and the head of the patient. At the rear of the head the inner perimetral surface of the band 45 is provided with the discharge passage 49 leading to the pipe 50.

Thus after the scalp protector has been positioned on the head and the necks 19 are closed, fluid may be circulated into the tubular band 45 causing it to expand and seal the scalp protector to the head. The fluid circulates by escaping through the small holes 48 and into the space between the scalp and the scalp protector from whence it discharges out of the passageway 49 and the tube 50. By controlling the extent of the openings in the passageways 48 and 49 different fluid pressures may be developed in the tube 45 and under the scalp protector 14, thereby sealing the scalp protector to the head and producing a pressure under the scalp protector to prevent seepage of condensate to the head from the steam chamber.

The fluid circulating through the tube 45 and on the patient's scalp also insulates the head from the steam chamber, thereby maintaining the scalp cool during the waving process.

In the spiral method the strands of hair 11 are wound on the spindles 51 as shown in detail in Fig. 9. The hair itself supports the spindle adjacent the neck through which the strand passes. The other ends of the spindles 51 may be supported by the independent stands 52 or they may be arranged to be supported by the clamps 53 on adjacent necks 19.

Referring now to Figs. 10 to 15, 54 represents a scalp spacer, a part of which is shown in detail in Fig. 14. This spacer comprises the flexible scalloped rim portion 55 provided with the snap fasteners 18. The inner portion of said rim is provided with the integral annular hollow band 56 which is supplied with the fluid inlet passage 57 at the rear thereof to form a connection with the pipe 58 leading to a source of fluid. 59 represents discharge ports in the upper wall of the band 56 which are located at the front of the head. These discharge ports function as inlet ports for the space 60 over the area of the scalp. The upper surface of the band 56 is shaped to form the trough 61. 62 represents a fluid discharge port for exhausting the chamber 60 through the drain pipe 63 near the rear of the spacer.

64 represents spacer head straps which are integral with the scalp spacer and are arranged to support the same. As shown these straps also divide the hair of the scalp into four parts preparatory to separating said hair into the strands 11. These straps may be made like a net for separating each strand. However, it is preferable to construct them as shown.

65 After the spacer 54 has been positioned on the head, the hair is divided off into the strands 11 to correspond to the necks 19 of the scalp protector 14 which is similar to that shown in Figs. 1 and 2.

70 When the hair strands 11 are drawn through the necks 19 and wound around on mandrels ready for waving, as previously described, the spreaders 65 may be placed over the scalp protector between the necks 19. These spreaders 75 are preferably made of semi-hard rubber so that

they, while conforming to the curvature of the scalp, will effect this spacing function. The ends of these spreaders are fastened together as at 65', making a group of said spacers into a single unit.

If the clamps 22, shown in Fig. 5, are employed to tightly clamp the hair in the necks 19 these spreaders 64 may be dispensed with as the upper portions of said clamps act as spreaders themselves.

After the spreaders have been positioned, the hood cap 66 is placed in position thereover, forming the steam chamber 27, as shown in Fig. 10. The hood cap, as well as the other caps, in preferably made of soft rubber or other suitable material and comprises the cap portion 67 and the thick annular rim 68. The lower and rearward portion of said cap is provided with the passageway 69 for connection to the pipe 70 which serves to supply steam to the chamber 27 and exhaust condensate therefrom.

The cap 66 is arranged to be snugly stretched over the other apparatus on the head and the heavy rim 68 tightly compresses against the tubular band 56 thereby sealing the steam chamber 27. The scalloped rim 55 of the scalp spacer and the rim of the scalp protector are then tightly folded up around the rim 68 and the snaps 18 secured to buttons on the hood cap as shown in Fig. 11. Thus the steam chamber 27 is completely sealed as an independent chamber on the patient's head.

The rear of the scalp spacer rim 55 is slotted and arranged to overlap around the pipe connections 50, 58 and 70 as shown in Fig. 11.

The operation and function of the sealing band 56 is similar to the band 45 shown in Fig. 7.

It is thus evident that by using greater pressures in the space between the scalp and the steam chamber than the pressures in the steam chamber, the danger of scalp burns from the steam or its condensate is avoided. Again by the use of a tubular pressure gasket surrounding the head the escape of moisture, steam or its condensates to the face or neck of the patient is prevented.

The advantage of doing away with the use of individual boxes or containers for each lock of hair is very marked. It affects a saving of time; it is more convenient; and the leakage of steam or its condensate is more easily prevented.

We claim:—

1. In apparatus for waving hair on the human head the combination of a scalp protector provided with a plurality of hollow necks through which the strands of hair are drawn and clamped, a hood forming a heating chamber with said scalp protector for enclosing the wound hair strands for treatment, and a fluid actuated band for sealing the scalp protector to the head and to said hood.

2. In apparatus for waving hair on the human head the combination of a scalp protector provided with a plurality of hollow necks through which the strands of hair are drawn and clamped, a hood forming a heating chamber with said scalp protector for enclosing the wound hair strands for treatment, and means for circulating a fluid and maintaining it under sufficient pressure between the scalp and the scalp protector to resist the passage of the heating medium to the scalp.

3. In a scalp protector the combination of a flexible cap, a plurality of necks on said cap, said necks having openings therethrough for re-

- ceiving strands of hair, said protector being arranged to coat with an outer closure to provide a common heating chamber for waving the strands of hair passing through said necks.

5. In a scalp protector the combination of a base portion, an upwardly extending neck integral with said base portion, said neck and said base having an opening therethrough for the passage of a strand of hair and ribs on the inner walls of said opening to form a seal.

5. The combination of a scalp spacer having a fluid actuated sealing band, a scalp protector arranged to telescope over said sealing band, and a hood member arranged to telescope over said 10 scalp protector and a rim on said spacer arranged to fasten on said hood.

6. In a container for waving hair on the human head, the combination of a scalp protector comprising a single piece of resilient material having a plurality of seals through which strands of hair are drawn and clamped, and a closure member having its perimetral portion arranged to engage the perimetral portion of said protector to complete the closure member.

20 7. In a container for waving hair on the human head, the combination of a scalp protector comprising a single piece of resilient material having a plurality of seals through which strands of hair are drawn and clamped, a closure member having its perimetral portion arranged to engage the perimetral portion of said protector to complete the closure member, and access means through the protector adjacent the lowermost portion thereof.

30 8. In a scalp protector for use in waving human hair, a cap formed of flexible material and provided with a plurality of apertures therethrough for receiving strands of hair, said cap being arranged to coat with a closure member to provide a common heating chamber for waving the strands of hair.

35 9. In apparatus for waving hair on the human head, the combination of a scalp protector comprising a single piece of resilient material having a base arranged for admitting a plurality of strands of hair to be waved, and a common closure member for covering said strands and having its perimetral portion arranged to engage the protector to complete the enclosure.

40 10. In apparatus for waving hair on the human head, the combination of a scalp protector comprising a single piece of resilient material having a base arranged for admitting a plurality of strands of hair to be waved, a common closure member for covering said strands and having its perimetral portion arranged to engage the protector to complete the enclosure, and access means at the lowermost portion of the enclosure for draining fluid therefrom.

45 11. In apparatus for waving hair on the human head, the combination of a scalp protector comprising a single piece of resilient material having a base arranged for admitting a plurality of strands of hair to be waved, a common closure member for covering said strands and having its perimetral portion arranged to engage the protector to complete the enclosure, and access means at the lowermost portion of the enclosure for draining fluid therefrom.

50 12. In a scalp protector a single piece of resilient material formed to provide a longitudinally slotted seal arranged to engage opposite sides of a strand of hair and a base extending laterally from the sides and walls of the seal, the walls of the said seal converging at either end to provide uniform thickness longitudinally of the seal when a clamp is applied thereto.

55 13. In a scalp protector the combination of a base portion, an upwardly extending neck integral with said base portion, said neck and said base having an opening therethrough for the passage of a strand of hair and ribs in staggered relation on the inner wall of the opening arranged to interengage to form a seal.

60 14. A scalp protector formed of flexible material and arranged to be placed on the head for use in waving the hair thereon, said protector having spaced apart openings through which strands of hair may be drawn for waving, and spacing means interposed at intervals between the protector and the scalp to provide clearance for a circulating medium to cool the scalp.

15. In apparatus for waving hair on the human head, the combination of a scalp protector having a hollow neck through which a strand of hair is drawn and clamped to be treated, means defining an enclosed space between the protector and the scalp, and means for introducing and retaining a fluid under pressure in said space to prevent hair treating agents from passing through the protector to the scalp.

20 16. In apparatus for waving hair on the human head, the combination of a scalp protector having a plurality of hollow necks through which the strands of hair are drawn and clamped, said scalp protector forming one side of a heating chamber in which the wound hair strands are treated, and means defining an enclosed space between the scalp and the protector for maintaining a fluid under sufficient pressure to penetrate any defects in the protector and prevent the heating medium from having access to the scalp.

25 17. In the waving of human hair by heating a coiled strand of the same in an enclosure, the method of preventing injury to the scalp which comprises providing an enclosed space between the wall of said enclosure and the scalp and maintaining a cooling fluid in said space under sufficient pressure to prevent the flow of hot fluid from the enclosure into said space.
